UNITED STATES PATENT OFFICE.

MARCUS M. BEEMAN, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT STAY OR SPRING.

1,069,222.

Specification of Letters Patent.

Patented Aug. 5, 1913.

Application filed November 5, 1908. Serial No. 461,227.

To all whom it may concern:

Be it known that I, MARCUS M. BEEMAN, a resident of Meadville, in the county of Crawford and State of Pennsylvania, have 5 invented a new and useful Improvement in Garment Stays or Springs, of which the following is a specification.

This invention relates to wire springs and more particularly to springs for use as garment stays and the like.

The object is to provide a spring which is perfectly yielding in all directions, which is so constructed that the bending stresses are not confined at any point or points so as 15 to avoid crystallization and breakage, and which is practically perfectly elastic so that it will not take a permanent set.

The invention comprises a spring as hereinafter described and claimed.

20 In the accompanying drawing Figure 1 is a face view of a garment stay embodying the invention; Fig. 2 is a cross section there-through; Fig. 3 is an edge view of the same; Fig. 4 is a face view of a modification; Fig. 5 is a view of a portion of the stay with its inclosed casing; Fig. 6 is a view showing the stay provided with a clasp; Fig. 7 is a face view of still another modification, and Fig. 8 is an edge view of 30 a modification.

The stay is formed from a continuous wire which is bent to form in succession two parallel series of closed eyes or coils 2, each being in excess of one complete turn of the 35 wire, and the ends of the coils being joined by the intermediate portions 3. The coils on one edge are coiled in one direction and those on the opposite edge are coiled in the opposite direction, so that the intermediate 40 portions 3 extend somewhat diagonally across the stay, but this is not essential. The coils themselves are twisted out of the plane of the stay, so that when the stay is contracted endwise the several coils will 45 pass one over the other. The coils on one side may be tilted in one direction and those of the other side tilted in the opposite direction, as shown in Fig. 8, or those 50 on the two sides tilted in the same direction, as shown in Fig. 3. This not only enables the coils to overlap when the spring shortens but also gives a greater thickness to the stay

thus giving greater strength to flatwise bending. The stay can be made either with the coils on each side edge slightly overlapping as in Fig. 7, or with slight spaces there-between as in Fig. 1, or with quite material spaces there-between as in Fig. 4. The stay is preferably concaved longitudinally, or has the transverse portions otherwise deflected from the plane of the stay as shown in Fig. 2. This increases the stiffness of the stay and also prevents the same from taking a permanent set when bent flatwise. The ends of the stay is finished with 55 the usual sheet metal tip 5, and is inclosed in the usual casing 6 which usually forms a portion of the fabric of the corset or other garment. To adapt it for clasps it will be surrounded with a sheet metal clip 7 to 60 which is secured a plate 8 provided with the usual key-hole slot 9 adapted to receive a stud 10 carried by a similar clip on the other clasp member.

The stay described is easy to manufacture 75 and is perfectly flexible in all directions. The coils at the edges of the stay and forming the ends of the loops, so to speak, allow for great flexibility to edgewise bending.

If desired, a plurality of wires may be 80 used in place of the single wire described.

What I claim is:

1. A garment stay comprising wire bent to form two series of closed eyes or coils forming the edges of the stay, each eye or 85 coil being in excess of one complete turn of the wire, and transverse portions connecting the ends of oppositely disposed coils, the coils being tilted in the plane of the stay, those on the two edges being tilted 90 in opposite directions, whereby when the stay is flexed said coils can slide over each other.

2. A garment stay comprising wire bent to form two series of closed eyes or coils 95 forming the edges of the stay, said coils being tilted in the plane of the stay, those coils on opposite edges being tilted in opposite directions, and transverse portions connecting the ends of oppositely disposed 100 coils, said stay being concaved longitudinally.

3. A corset stay comprising wire bent at intervals to form two series of oppositely

disposed closed eyes or coils and transverse crossings connecting said eyes or coils, each of said eyes or coils being in excess of one complete turn of the wire and tilted in the 5 plane of the stay, adjacent eyes or coils longitudinally of the stay slightly overlapping each other.

In testimony whereof, I have hereunto set my hand.

MARCUS M. BEEMAN.
